UNITED STATES PATENT OFFICE.

PHILO WILLIAM CASLER, OF LITTLEFALLS, NEW YORK

COVER FOR STATIONARY WASHTUBS.

SPECIFICATION forming part of Letters Patent No. 761,147, dated May 31, 1904.

Application filed September 29, 1902. Serial No. 125,144. (No model.)

To all whom it may concern:

Be it known that I, PHILO WILLIAM CASLER, a citizen of the United States, and a resident of Littlefalls, in the county of Herkimer and 5 State of New York, have invented certain new and useful Improvements in Covers for Stationary Washtubs, of which the following is a specification.

This invention relates to covers for stationary washtubs; and the object of the present improvement is to provide an inexpensive 10 cover of this class having automatic means whereby perfect joints are maintained between the several pieces composing the cover when 15 the same is subjected to either heat or moisture.

My improvement consists, essentially, of a cover for stationary washtubs which is composed of a number of boards or strips of wood 20 held together by means of yielding clamping devices which act as automatic take-ups or followers for the boards and prevent the joints from opening when the boards shrink. Such devices also permit the boards to swell 25 or expand without affecting the shape of the cover.

Referring to the accompanying drawings, Figure 1 is a perspective view of my improved 30 cover. Fig. 2 is a sectional view of the cover, showing the yielding clamping device for the same. Fig. 3 is an enlarged detail view of the cover.

Similar letters refer to similar parts in the several views.

35 A represents the boards of which my improved cover is composed, said boards being preferably provided with tongue-and-groove joints A'. These boards are held together by means of a yielding clamping device comprising a rod B, having a head B' at one end and a nut B² at the other. The outer board of the cover is provided with a cavity or socket C. Interposed between the bottom of this socket and the head of the rod is a spiral spring D. 40 This spring acts as a take-up or follower for the boards when the same shrink or contract. The spring permits the boards to expand with-

out warping or affecting the shape of the cover.

E represents bushings for the rods, which 50 are so secured to the boards that they extend transversely across the joints of the boards, thus acting as dowel-pins and preventing any longitudinal movement of the rods and preventing any binding of same when the boards 55 swell or expand. In order to prevent the said bushings from sticking to the boards when the same expand, the outsides of the bushings are made tapered toward the ends.

It will be seen that by the above construction 60 I provide an inexpensive cover particularly adapted for washtubs or other articles of manufacture which are alternately subjected to heat and moisture. It is exceedingly easy to manufacture, as no glue is used for 65 the joints between the boards, the same being simply matched or placed with their longitudinal edges against each other and held together by means of the rods above mentioned.

I do not desire to limit myself to the particular construction herein shown and described, as some changes may be made therein without departing from the spirit and scope 70 of my invention.

What I claim as new, and desire to secure by Letters Patent, is—

1. A cover for stationary washtubs composed of a number of boards or strips loosely arranged side by side, a clamping-rod extending 80 transversely through the strips, said rod being provided at its ends with heads forming stops for the outer strips of the cover, a spiral spring interposed between one of the said stops and outer strips of the said cover, bushing 85 for the clamping-rod extending transversely across the joints of the strips, substantially as described.

2. A cover for stationary washtubs composed of a number of strips loosely arranged 90 side by side, an elastic clamping device for the strips, in combination with means for preventing the strips from moving longitudinally, substantially as described.

3. A cover for stationary washtubs composed of a number of strips loosely arranged side by side an elastic clamping device for the strips, substantially as described.
- 5 4. A cover for stationary washtubs composed of a number of strips loosely arranged side by side a clamping-rod for said strips,

in combination with automatic transverse take-ups for the strips, substantially as described.

PHILO WILLIAM CASLER.
